CLAIM

The ornamental design for a compressible traction device, as shown and described.

DESCRIPTION

FIG. 1 is a perspective view of a compressible traction device showing my new design;

FIG. 2 is a top plan view thereof;

FIG. 3 is a right side elevation view thereof;

FIG. 4 is a bottom plan view thereof;

FIG. 5 is a front elevation view thereof; and,

FIG. 6 is a rear elevation view thereof, shown at a larger scale.

The portion of FIG. 6 shown inside an area bounded by broken line curve is for environmental purposes only and forms no part of the claimed design.
